UNITED STATES PATENT OFFICE.

NED A. OCHILTREE, OF OMAHA, NEBRASKA, ASSIGNOR TO CONCRETE ENGINEERING COMPANY, OF OMAHA, NEBRASKA, A CORPORATION OF NEBRASKA.

FENCE POST.

Application filed January 30, 1928. Serial No. 250,368.

This invention pertains to fence posts and more particularly to tubular metal posts such as those made from old boiler tubes and the like.

5 Fence posts of the character above mentioned have been known and used for a considerable period of time but their use has not been as extensive as it might otherwise have been were it not for several difficulties 10 and disadvantages encountered with their use. In the first place if the tube be left in its natural open ended form when used as a fence post, while the top end may afford sufficient impact area to enable each driving 15 blow struck it to be fully effective without splitting or distorting the post or the post end, the end of the post being open wide permits rain and frost to get in and deteriorate the metal.

20 To overcome this difficulty and disadvantage it has become more or less common to pinch or flatten the driving end after the manner illustrated in Griswold Patent No. 378,051 or that shown and described in the 25 Carlson and Wilcox Patent No. 1,609,795. However, such construction or arrangement also has serious disadvantages which in some measure offset the advantage gained by closing the end. When the tube is pinched or 30 flattened at the top a very narrow driving surface is presented to the maul or other device used in driving the post in, which increases the chances of missing the post entirely when striking the blow and very often 35 causes the post to be battered or broken because the blow is a glancing one. Then too such a driving edge because it is an edge, is easily flattened or battered over when driven with a sledge or maul and sometimes 40 tends to buckle over. Moreover this type of head very frequently opens up when driven and permits moisture to enter within the interior. I have devised an arrangement 45 whereby the end of a tubular metal post may be closed off entirely to prevent the entrance of water or moisture, one which will provide a driving area properly distributed for its purpose, and one which will be stronger and more effective than prior constructions as 50 well as one which will overcome the disadvantages and difficulties encountered heretofore. Such may be said to be the primary object of my invention.

Other objects, the advantages and uses of

my invention will be and should become apparent after reading the following description and claims and after viewing the drawing in which:

Fig. 1 is an elevational view of a tubular steel post embodying the invention.

Fig. 2 is an elevational view of the same steel post looking at the same from the right or left of Fig. 1 and

Fig. 3 is an enlarged perspective view of the top end of the post illustrated in Figs. 1 and 2.

Referring more particularly to the drawing, 1 designates a tubular steel fence post which may have served a previously useful life as a tube in a boiler. In order to facilitate driving such post its bottom end is flattened off on a taper as illustrated at 2 on opposite sides to make the same wedge shaped and if desired, as is often the case, the bottom edge may be beveled off as illustrated at 3 to point the same. The top or driving end according to the invention is pinched in from opposite sides, that is, at the ends of a diameter and adjacent thereto as indicated at 4 to provide a stem portion 5 while the ends of the portion 5 are spread laterally thereof by pressure applied at right angles to the direction in which pressure is applied to the portions 4, that is, to the portions 6. The net result is the provision of areas 7 the longest dimensions of which in the form illustrated extend at right angles to the length of the portion 5 whereby an I-beam end section for the post is provided.

The I-beam section need not extend for a very great distance along the length of the post but for a 6 ft. post 2 ins. in diameter I have found it preferable to have the I-beam section extend a little over an inch. This arrangement in construction materially strengthens the driving end of the post and affords an effective driving area, prevents the post from opening up during the driving, and in short overcomes all of the difficulties and disadvantages heretofore met in utilizing tubular metal posts. The I-beam type of head being approximately of the same general diameter longitudinally of the I as the main section of the post below the head, results in practically every driving blow imparted thereto being communicated directly to the wall of the tube below the head without any flattening or battering effects. The

result is a post which is much easier to drive and one which may be driven absolutely straight. Since the top does not batter or open up when hammered with a sledge or 5 maul it remains sealed against the entrance of moisture.

In order that fence wire, woven or stranded, may be secured to the post, the tubular portion of each may be drilled through from 10 one side to the other at spaced intervals as shown at 8. Thus when the fencing is to be secured to the post, a tie wire or the like may be placed about a strand of the fencing threaded through one of the holes 8 and secured to the post in any desirable manner.

While I have illustrated and described the preferred embodiment of my invention it will be appreciated that it is susceptible of modification and changes without departure 20 from the spirit of the invention or the scope of the appended claims.

I claim:

1. An article of manufacture, a tubular metal fence post having its top end formed 25 into I-beam shape.
2. An article of manufacture, a tubular metal fence post having its driving end for

a relatively short distance along the post crimped into I-beam shape.

3. An article of manufacture, a fence post 30 made of a single piece of cylindrical metal tubing, one end of said piece having portions collapsed so as to meet into a plane surface and having the sides of the flattened end distorted toward one another a sufficient distance to bring them at least to the original diameter of the post thereat.

4. An article of manufacture, a fence post made of a single piece of metal tubing, one 40 end of said piece having portions at and adjacent the ends of a diameter flattened together and having the sides of the flattened end distorted toward one another a sufficient distance to bring them at least to the original diameter of the post thereat, whereby 45 the said end of the post is I-beam shape in cross-section, the stem of the I in cross-section being of substantially greater length than the length of either end thereof in cross-section.

In witness of the foregoing I affix my signature.

NED A. OCHILTREE.
